LADY'S STOCKING

William Nebel, Charlotte, N. C.

Application June 4, 1949, Serial No. 3,046

Term of patent 14 years

(Cl. D47—7)

To all whom it may concern:

Be it known that I, William Nebel, a citizen of the United States of America, residing at Charlotte, in the county of Mecklenburg, State of North Carolina, have invented a new, original, and ornamental Design for a Lady's Stocking, of which the following is a specification, reference being had to the accompanying drawings, forming a part thereof.

I claim:

The ornamental design for a lady's stocking, substantially as shown.

WILLIAM NEBEL.
